METHOD AND APPARATUS FOR
HOISTING POLES

Robert R. McCamish, 4546 E. Nevada, Fresno, Calif.
Filed Apr. 23, 1957, Ser. No. 654,595
10 Claims. (Cl. 214—3)

The present invention relates to a method and apparatus for hoisting or raising poles and more particularly to a powered hoisting implement, or pike, especially adapted to erect and set poles in precisely vertical, or other generally upright, positions.

Crews of seven or eight workmen are usually assigned to erect power poles for electrical transmission lines according to conventional practices. The poles are usually inserted in holes dug for the purpose with the aid of a cable connected to a truck hoist. While the cable is still connected to a pole, the workmen shove elongated, rigid hoisting implements having sharpened points into the pole from all sides in order to steady, guide and position the pole. These implements are known in the art as pikes and are hereinafter so designated. Obviously considerable teamwork is required between the workmen for satisfactory results. Conventional pikes are frequently about eighteen feet long and of metal or wood. With the pikes impaling the pole, the workmen increase or relieve pressure on various sides of the pole and thus attempt to hoist the pole into precise position. After the position has been obtained, dirt is filled in the hole around the pole and tamped down.

This is a tedious, time consuming, and somewhat hazardous task. When the pikes are made of wood, workmen frequently get splinters in their hands. It has been known for heavy pikes to fall onto workmen imposing serious injury. Further, sprained backs and other undue muscular strains result from suddenly having to bear part of the weight of a pole while attempting to bring it into vertical position.

Accordingly, it is an object of the present invention to provide an improved method and apparatus for erecting poles and the like.

Another object is to provide a powered extensible and retractable pike.

Another object is to minimize or prevent muscular and bodily injury and/or fatigue in erecting poles.

Another object is to enable the hoisting of poles by mechanical rather than manual means.

Another object is to reduce the time and labor incident to the hoisting of poles and the expenses incident thereto.

Another object, in a power operated pike adapted to penetrate a pole, is to prevent undue impalement of the pole with the pike and to facilitate subsequent removal thereof.

Other objects are to provide a hoisting implement of the character described which is simple in construction and operation, dependable in action, and durable in form.

These and other objects will become more fully apparent upon reference to the following description.

In the drawings:

FIG. 1 is a perspective view of two of the pikes of the present invention shown as used in raising a power pole into vertical position.

FIG. 2 is a somewhat enlarged elevation, with portions in longitudinal section and other portions broken away, of one of the pikes of FIG. 1 with the cap removed.

FIG. 3 is a fragmentary side elevation of the upper end of the pike of FIG. 2 showing the cap fitted on said upper end.

FIG. 4 is a fragmentary front elevation, partially in section, of the lower end of the pike and showing in particular a supporting base therefor.

2

FIG. 5 is a somewhat enlarged fragmentary longitudinal section of a portion of the pike particularly showing a check valve passage in an hydraulic system forming part of the implement.

FIG. 6 is a somewhat enlarged longitudinal section of the lower end of the hoisting implement showing other passageways in the hydraulic system.

Referring more particularly to the accompanying drawing, a mechanically powered pike is generally indicated by the numeral 10 in FIG. 1. The pike provides a lower body 11 having an upwardly disposed internally threaded socket 12.

An hydraulic ram 16 includes an elongated ram cylinder 17 having a lower externally threaded end 18 screw-threaded into the socket 12 and an upper externally threaded end 19. A nut 20 is screw-threaded over the upper end of the ram cylinder and provides a central bore axially aligned with the ram cylinder. An elongated cylindrical tube 21 is extended between the nut and the body in circumscribing, peripherally spaced, concentric relation to the ram cylinder. The tube is in fluid-tight engagement with the nut and the body and together with the ram cylinder defines a fluid reservoir 22.

An elongated piston rod 26 is mounted for slidable movement in the ram cylinder 17 and has a lower end 27 terminating in external threads. A cup piston 30 is fitted over the lower end of the rod and a nut 32 is screw-threaded on said lower end to retain the piston on the rod. The piston rod has an upper end slidably extended through the bore of the nut 20. The invention is not to be limited to the use of an hydraulic ram but other telescopic extension devices, such as a mechanical jack, may be employed. However, the described hydraulic ram has marked advantages for the purpose.

An elongated, cylindrical outer sleeve 36 is concentrically slidably fitted over the tube 21 for longitudinal slidable movement on the tube. The sleeve has an open lower end terminating adjacent to the lower end of the tube when the piston 30 is fully retracted and an upper end secured, as by welding, to a head 38 on the upper end of the piston rod 26.

The body 11 provides a substantially cylindrical bore 40, constituting a pump cylinder, positioned with its longitudinal axes extended upwardly in acute angular relation to the axis of the socket 12 and opening exteriorly of the body. A packing nut 41 having a central bore is screw-threaded into the pump cylinder 40, and an elongated pump piston rod 42 is longitudinally slidably fitted in the pump cylinder and the bore of the packing nut. The pump piston rod has a lower end 43 over which is fitted a backing washer 44, and a cup piston 45. A piston retainer 46 is secured to the pump piston rod endwardly of the piston.

Brackets 50 are upwardly extended from the body 11 on opposite sides of the pump cylinder 40 and mount a horizontal pivot pin 51 therein. A handle socket 52 is journaled on the pivot pin, and a further pin 53 connects the handle socket to the pump piston rod 42. A pump handle 54 is provided for releasable insertion into the handle socket for moving the pump piston rod longitudinally inwardly and outwardly of the pump cylinder 40.

The body 11 has a check valve passage 60, best seen in FIG. 5, including an inner cylindrical section 61, an intermediate cylindrical section 62, and an outer cylindrical section 63 opening externally of the body, each of successively greater diameter. A valve plug 64 is screw-threaded into the open end of the valve passage, and a valve seal 65 positioned against the plug. A suction ball 67 is yieldably urged against the mouth of the inner section by means of a suction spring 68, and a pressure ball 69 is yieldably urged against the mouth of

the intermediate section by means of a pressure spring 70. The latter spring also bears against the valve seal.

An extension passage 75 interconnects the inner section 61 of the check valve passage 60 with the reservoir 22. A ram passage 76 interconnects the outer section 63 with the ram cylinder 17 at the lower end thereof beneath the piston 30. The ram passage has an inner end portion, and an outer end extension 78 in which is screw-threaded a packing nut 77. A release valve 79 is screw-threaded into a bore in the packing nut having an inner end adapted to seat in the inner end portion of the ram passage. The body also has a retraction reservoir passage 80 interconnecting the outer end portion 78 of the ram passage and the reservoir. When the release valve is backed off, fluid communication is established between the reservoir and the ram passage. When the release valve is tightened inwardly, however, this communication is blocked. Still further, the body has a pump cylinder passage 81 interconnecting the intermediate section of passage 60 and the lower end of the pump cylinder 40.

An elongated rigid shank 85 has a lower end 86 secured, as by welding, to the upper end of the outer sleeve 36. The shank is axially extended from the sleeve, and thus the ram piston rod 26, and has an upper end 87 of reduced diameter. The upper end has a slightly curved, tapered tip 88 which is preferably somewhat flattened though terminating in a sharpened knife edge. A stop collar 89 is secured to the upper end of the shank at an angle of substantially 45° with the shank and immediately below the tip.

An eyelet 95 is secured to the shank 85 adjacent to the upper end 87, and a coiled tension spring 96 has an end connected to the eyelet. A substantially cylindrical elongated hollow cap 97 provides a closed upper end 98 and an open lower end 99 circumscribed by a beveled edge at an angle of approximately 45° with the longitudinal axis of the cap. The spring provides an extended end which is connected to the cap adjacent to its upper end by another eyelet 100. The spring is of such length as to permit placement of the cap over the tip 88 of the shank with the lower beveled edge of the cap engaging the upper surface of the collar 89. In this position the spring exerts slight pressure on the cap longitudinally of the shank for dependably holding it in position. The cap, of course, is conveniently removed by sliding it upwardly off from the tip and allowing it to hang freely from the shank.

The body 11 of the pike 10 is secured, as by welding, to a channel-shaped main base 105 including a central panel 106, and a pair of downwardly extended side panels 107. A downwardly concave, fracto-cylindrical bearing 108 is secured to the underside of the central panel between the side panels and substantially parallel to the latter.

An auxiliary base 112 is provided including a substantially rectangular plate 113, spaced substantially parallel side flanges 114 rigidly upwardly extended from the plate, and a rigid shaft 115 interconnecting the side flanges in spaced relation to the plate.

An elongated preferably adjusted flexible tie member 120, such as a chain provides an end 121 adapted for connection to either the main base 105 or to the auxiliary base 112 by means of eyelets 123 and 124 respectively secured to said bases, and an opposite end 125 to which is connected a hook 126.

Operation

The operation of the described embodiment of the subject invention is believed to be readily apparent and is briefly described at this point. The operation is best understood in connection with the erection of a power pole, indicated at 130, having a lower end 131 and an upwardly extended end 132.

While describing the operation of the pike 10, a novel method of erecting a pole is also described. Initially, a

hole 135 is dug in the ground 136 so as to provide a bottom wall 137 and an upstanding circumscribing side wall 138 terminating in an upper edge 139. It is assumed for illustrative convenience that a concrete pavement 140 is located near the hole.

The lower end 131 of the pole 130 is inserted into the hole 135 with the aid of a cable and truck hoist, neither of which are shown, but which are conventionally used in such an operation. The lower end of the pole rests 10 on the bottom wall 137 of the hole and the pole leans against the upper edge 139 toward the pavement. With the cable, not shown, still connected to the pole, the hole is partially filled, preferably about one-half, with dirt 145 so that the lower end of the pole is surrounded with dirt. 15 This dirt is then tamped in around the pole with the pole still in slightly inclined position.

Next, two pikes 10 are placed on the side of the pole 130 toward which the pole leans. The auxiliary base 112 of each pike is positioned with the plate 113 flush against 20 the pavement 140 and with the shaft 115 substantially tangential to a circle concentric to the hole 135 and in spaced relation thereto. The chain 120 is connected to the eyelet 124 and the hook 126 is engaged over the upper edge 139 of the hole, or the edge of the pavement 25 between the hole and the auxiliary base, as indicated in dashed lines in FIG. 1; the chain is looped around the pole and connected to a link of the chain, as shown in full lines in FIG. 1; or the chain is otherwise anchored in the ground so that movement of the base away from the 30 pole is resisted. With the ram 16 retracted, the bearing 108 is fitted over the shaft 115 and the pike leaned against the pole with the tip 88 in engagement therewith. The cap 97 is, of course, first removed. The length of the 35 chain, that is, the distance of the base 112 from the hole is such that the angle of the pike with the ground is approximately 45°. The bearing, in rotating on the shaft, enables positioning the pike at 45°, or other desired angle.

The pump handle 54 is inserted into the socket 52 and the pump piston rod 42 reciprocated in the pump cylinder 40. On the up-stroke, fluid is drawn through the reservoir passage 75 into the intermediate section 62 of the check valve passage 60, and on the down-stroke, said fluid in the intermediate section is forced into the outer section and through the ram passage 76 into the cylinder 17 to extend the piston rod 26 and thus the shank 85. Continued pumping of the handle 54 causes the tip 88 to penetrate the pole. The stop collar 89 limits this penetration. Because of the angle of the pike and the angle of the collar, the latter is in substantially flat engagement 45 with the pole. The rotatably engaged bearing 108 and shaft 115 preclude imposition of bending forces on the pike by allowing the pike to pivot around shaft 115 as a horizontal axis.

As the pikes 10 are extended, the pole 130 is shoved 50 away from them toward a vertical position. Upon reaching a vertical, extension of the pikes is stopped, and the hole is completely filled with dirt 145.

However, partial filling of the hole 135 with dirt 145 55 enables movement of the pole 130 into vertical position by a preferred procedure. The pikes are extended to move the pole slightly beyond a vertical to place the dirt 146 between the pole on the side of the pole opposite to the pikes and the side wall 135 of the hole under compression. Although this is preferably purposely done, it even may occur unintentionally. In any event the dirt in the hole provides a resilient cushion inasmuch as it is somewhat resiliently compressible and forces the pole back toward a vertical position upon slightly contracting 60 the ram 16. It will be evident that the dirt acts as an automatic and controllable force on the opposite side of the pole from the pikes so that a latitude of adjustment is afforded for bringing the pole into precise position. Thus with the rams both slightly over extended, great finesse can be achieved in precise positioning by placing

a level or other position checking means against the pole and gradually releasing hydraulic fluid from either or both rams by means of the valves 79 so that the resiliently compacted soil urges the pole into position.

After the pole 130 is positioned and with the pikes 10 still in position, the hole is completely filled with dirt 145 and tamped down. The pikes are then contracted and removed from the pole by backing off the release valve 79 to allow fluid to escape from the ram cylinder 17 into the reservoir 22. As above stated, the collars 89, in preventing undue penetration, facilitate disengagement from the poles.

In working on ordinary ground, the auxiliary base 112 is usually not employed. The main base 105 is then used since the side panels 109 frictionally engage or slightly 15 penetrate the earth to hold the base in position. In this case, the chain 120 can also be employed, as before.

It will be evident from the foregoing that the powered pike 10 offers a decided improvement over the pikes of the prior art. The device reduces the time and labor required in erecting poles and avoids the hazards and strain previously encountered. In practice, a line of power poles extending over many miles of mountainous terrain has been erected by only three men using pikes of the 20 present invention as compared with the usually required crew of seven or eight needed for even level ground operation.

Although the invention has been herein shown and described in what is conceived to be the most practical and preferred method and embodiment, it is recognized that departures may be made therefrom within the scope of the invention, which is not to be limited to the details disclosed herein but is to be accorded the full scope of the claims so as to embrace any and all equivalent methods, devices, and apparatus.

Having described my invention, what I claim as new and desire to secure by Letters Patent is:

1. An hydraulic pike for hoisting an elongated pole lower end inserted into a hole in the ground and prior to being hoisted by said pike is in angular relation to the ground comprising a base member adapted to rest on the ground in spaced relation to the hole, an hydraulic ram including a cylinder and a piston rod longitudinally reciprocally mounted in the cylinder for extension and retraction relative to the cylinder, means mounting the cylinder on the back, an elongated rigid shank connected to the piston rod and axially extended therefrom having a single upper sharpened pole penetrating end adapted to engage the pole in upwardly spaced relation from the ground, an elongated outer guide sleeve longitudinally slidably fitted in circumscribing relation to the ram and having an upper end rigidly connected to the shank for longitudinal movement therewith relative to the ram, means connected to the ram for extending the piston rod to drive the penetrating end into the pole and for retracting the rod to remove said end from the pole, the sleeve serving to impart strength to the connection between the shank and the ram and particularly when the piston rod is extended and weight of a pole is borne by the pike thereby resisting bending forces and facilitating free slideable movement of the piston rod in the cylinder and a stop collar connected to the shank adjacent to said penetrating end transversely of the shank and engageable with the pole upon extension of the ram for limiting penetration of said end into the pole whereby extension of the ram urges the pole into substantially vertical position.

2. The pike of claim 1 wherein the tip is slightly curved, is tapered to a point, and is somewhat flattened transversely thereof; wherein the shank has a longitudinal concentric axis; and wherein the collar is annular, provides a plane upper surface and is in oblique angular relation to the axis of the shank and in substantially the same angular relation thereto as the angular relation between the shank and the ground when the pike is in position against a pole so that the upper surface of the collar

is adapted for flush engagement with a pole to enable maximum application of pressure to the pole.

3. The pike of claim 1 wherein the mounting means includes a body having a socket into which the ram cylinder is fitted, an annular nut connected to the cylinder in spaced relation to the body and slidably receiving the piston rod, an elongated tube in circumscribing circumferentially spaced relation to the ram cylinder having opposite ends in fluid-tight engagement with the nut and with the body and defining a reservoir with the ram cylinder, the sleeve being in slideable fitted engagement over the tube, the body including a pump cylinder and fluid passageways interconnecting the pump cylinder, the ram cylinder, and the fluid reservoir, a pump piston rod longitudinally reciprocally mounted in the pump cylinder for pumping fluid from the reservoir into the ram cylinder for extending the shank, a handle connected to the pump piston rod for enabling reciprocation thereof and extended outwardly from the sleeve adjacent to the base, and means mounted in the body releasably extended into the passageways for releasing fluid from the ram cylinder for return to the reservoir to enable retraction of the shank.

4. An hydraulic pike for hoisting an elongated pole into substantially vertical position, which pole has a lower end inserted into a hole in the ground and prior to being hoisted by said pike is in angular relation to the ground, comprising an hydraulic ram including a cylinder and a piston rod longitudinally reciprocally mounted in the cylinder for extension and retraction relative to the cylinder, an elongated rigid shank connected to the piston rod and axially extended therefrom having an upper sharpened pole penetrating end adapted to engage the pole in upwardly spaced relation from the ground, an elongated outer guide sleeve longitudinally slidably fitted in circumscribing relation to the ram and having an upper end rigidly connected to the shank for longitudinal movement therewith relative to the ram, means connected to the ram for extending the piston rod to drive the penetrating end into the pole and to raise the pole and for retracting the rod to remove said end from the pole, the sleeve serving to impart strength to the connection between the shank and the ram and particularly when the piston rod is extended and weight of a pole is borne by the pike thereby resisting bending forces and facilitating free slideable movement of the piston rod in the cylinder, a stop collar connected to the shank adjacent to said penetrating end transversely of the shank and engageable with the pole upon extension of the ram for limiting penetration of said end into the pole whereby extension of the ram urges the pole into substantially vertical position, a substantially rectangular plate adapted to be supported on the ground in spaced relation to the hole, spaced flanges upstanding from the plate, a shaft rigidly interconnecting the flanges adapted to be positioned substantially tangential to a circle concentric to the hole, a concave bearing rotatably fitted on the shaft, and means mounting the bearing on the cylinder of the ram in substantially perpendicular relation thereto for enabling pivotal movement of the ram and the shank around said shaft as an axis toward and away from the pole during extension and retraction of the ram whereby bending forces are not imposed on the ram and the shaft.

5. A method for erecting an elongated power pole having a lower end comprising digging a hole in the ground having a substantially horizontal bottom and a substantially vertical circumscribing side wall terminating in an upper edge, inserting the lower end of the pole in the hole and resting said lower end on said bottom with the pole leaning against the upper edge of the hole in angular relation to the surface of the ground, filling substantially half of the hole around the pole with dirt having resilient compressibility so that the lower end of the pole in the hole is surrounded by dirt, tamping said dirt in the hole until it is packed around the lower end of the pole, ap-

plying pressure to the pole in vertically spaced relation to the ground to move the pole from said angular position to slightly beyond a vertical position so as to place the dirt under compression between the pole and the sidewall on the opposite side of the pole from the side on which pressure is applied, gradually relieving the pressure on the pole until the resilience of said compressed dirt returns the pole to substantially vertical position, completely filling the hole with dirt around the pole, tamping said dirt to pack it tightly around the pole, and removing said pressure.

6. An apparatus for hoisting an elongated pole, such as those employed in connection with electrical power lines, into substantially vertical position, the pole having a lower end inserted into a hole in the ground and, prior to such hoisting, being in angular relation to the ground, comprising a pair of elongated, individually longitudinally continuously adjustable hydraulic pikes individually including base members adapted to rest on the ground in spaced relation to each other and to the hole on the side of the hole toward which the pole is leaning and in triangular relationship with the hole, hydraulic rams including cylinders individually secured to their respective bases and piston rods longitudinally reciprocally mounted in their respective cylinders for extension and retraction relative to the cylinders, elongated rigid shanks connected to the piston rods and axially extended therefrom having upper sharpened pole penetrating ends adapted to engage the pole in upwardly spaced relation from the ground and in closely adjacent peripherally spaced relation on the side of the pole toward which the pole is leaning, means connected to the rams for extending the piston rods to drive the penetrating ends into the pole and for retracting the rods to remove said ends from the pole, stop collars individually connected to the shank adjacent to their respective penetrating ends, transversely of the shanks, and engageable with the pole upon extension of their respective rams for limiting penetration of said ends into the pole whereby extension of the rams urges the pole into substantially vertical position, and tension members individually interconnecting the base members and the pole adjacent to the ground anchoring the base members in predetermined substantially fixed spaced relation to the hole.

7. An hydraulic pike for hoisting elongated poles into erect positions comprising a base member adapted to rest on the ground, an elongated hydraulic ram having opposite ends and a substantially smooth cylindrical periphery, controlled hydraulic means connected to the ram for longitudinally extending and contracting the ram, an elongated rigid shank connected to the end of the ram opposite from the base and extended longitudinally from the ram in substantial alignment with contraction and extension movement thereof, a shank having an extended end providing a sharpened tip endwardly extended therefrom, a stop collar mounted on the shank in spaced adjacent relation to the tip having a pole engaging surface obliquely related to the shank, and a sleeve rigidly connected to the shank and slidably fitted to the cylindrical periphery of the ram to resist misalignment of the shank with said contraction and extension movement of the ram.

8. An hydraulic pike for hoisting elongated poles into erect position comprising a base member adapted to rest on the ground, an hydraulic ram having a cylinder pro-

viding a substantially cylindrical peripheral portion and a piston mounted for reciprocal movement in the cylinder and having a piston rod extended from the cylinder, controlled hydraulic means connected to the cylinder of the ram for longitudinally extending and contracting the piston rod from the cylinder, means mounting the cylinder on the base member, an elongated shank rigidly connected to the piston rod in longitudinal alignment therewith, the shank having an extended end providing a sharpened tip for pole engagement, a stop collar mounted on the shank adjacent to the tip having a pole engaging surface obliquely related to the shank, and a sleeve rigidly connected to the shank and slidably received on the peripheral portion of the cylinder of the ram to resist misalignment of the shank with the piston rod during contraction and extension movement thereof.

9. A method for setting an elongated pole having a lower end, in a hole previously provided in the ground comprising placing the lower end of the pole in the hole with the pole upwardly inclined therefrom whereby the pole has an underside, placing dirt having resilient compressibility in the hole about the pole, applying independently controlled lifting pressures to the underside of the pole along two angularly related lines of force spaced transversely of the pole to lift the pole to approximately a desired ultimate substantially upright position whereby dirt is resiliently compressed in the hole on the side of the pole opposite to said lines of force, and independently regulating said pressures in relation to the resilient compression of the dirt to achieve movement of the pole to said ultimate position in selected universal direction.

10. A method for setting an elongated pole having a lower end, in a hole previously provided in the ground comprising placing the lower end of the pole in the hole with the pole upwardly inclined therefrom whereby the pole has an underside, filling substantially the lower half of the hole about the pole with dirt having resilient compressibility, applying independently controlled lifting pressures having horizontal components of force to the underside of the pole along two angularly related lines of force spaced peripherally of the pole to lift the pole to approximately a desired ultimate substantially upright position whereby dirt is resiliently compressed in the hole on the side of the pole opposite to said lines of force, and independently and selectively increasing and decreasing said pressures in relation to resilient compression of the dirt whereby when either pressure is substantially greater than the resilient compression of the dirt the pole moves in the direction of said pressure and when either pressure is substantially less than the resilient compression of the dirt the pole moves in opposition to said pressure until the pole reaches said ultimate position, and filling the remainder of the hole to hold the pole in said position while the pole is still subject to said pressures.
